UNITED STATES PATENT OFFICE.

JOHN L. NUTE, OF CHAMBERSBURG, PENNSYLVANIA, ASSIGNOR OF ONE-THIRD TO
JESSE A. CHILCOTE, OF ALTOONA, PENNSYLVANIA.

COMBINATION TAIL LIGHT AND SIGNAL.

Application filed August 23, 1923. Serial No. 658,975.

To all whom it may concern:

Be it known that I, JOHN L. NUTE, a citizen of the United States, residing at Chambersburg, in the county of Franklin 5 and State of Pennsylvania, have invented a new and useful Combination Tail Light and Signal, of which the following is a specification.

This invention aims to provide a simple 10 means whereby the driver of a vehicle may indicate to persons in the rear of a vehicle, the intentions of the driver of the vehicle relating to stopping, proceeding and turning either to the right or to the left.

It is within the province of the disclosure 15 to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:

Figure 1 shows in elevation, a device 30 constructed in accordance with the invention; Figure 2 is a cross section on the line 2—2 of Figure 1; Figure 3 is an elevation showing the signal; Figure 4 is an end elevation of the signal; Figure 5 is a longitudinal section of the signal; Figure 6 is a cross section on the line 6—6 of Figure 5; Figure 7 is an elevation showing the keeper; Figure 8 is a diagrammatic view illustrating 35 the various markings on the surfaces of the signal body.

In carrying out the invention a bracket 1 is mounted on the rear portion of an automobile and carries a fixed tubular support 2 which is disposed horizontally. On the support 2 is mounted a keeper 4 provided with spaced seats 5. An electric lamp 3 is detachably mounted on the end of the support 2 and the conductors 33 for the lamp lead backwardly through the tubular support 2.

The signal comprises a casing denoted generally by the numeral 6 and including

an outer end plate 7 having an opening 8. A transparent pane 9 extends across the opening 8 and is held in a recess 10 formed in the inner surface of the end plate 7. The casing of the signal embodies an inner end plate 11. The body of the signal casing is rectangular in cross section and may be made of glass or any other suitable material. The body of the signal is colored on its various surfaces as may be required. The ends of the body 12 are received in grooves 14 formed in the inner surfaces of the end plates 7 and 11. The plates 7 and 11 have outstanding ears 15. Securing elements, such as screws 16, are journaled in the ears 15 of the end plate 7 and are threaded as at 17, into the ears 15 of the end plate 11. The heads 18 of the securing elements engage the ears 15 of the end plate 7. The construction is such, obviously, that the various constituent portions of the signal are held together securely but detachably. 75 The support 2 passes through the plate 11, the signal thus being supported for rotation on the member 2. A pulley 19 is located between the keeper 4 and the end plate 11. The end plate 11 has a polygonal projection 20 received in a correspondingly shaped recess 21 formed in the pulley 19. Thus, the pulley is held to the signal so that when rotation is imparted to the pulley, the signal will be rotated likewise. 85

The end plate 11 of the signal, and the pulley 19 are supplied with cooperating bores defining a passage 22. A screw plug 23 is threaded into the bore of the end plate 11. A compression spring 24 is disposed 90 in the passage 22 and bears against a ball latch 25, disposed in the passage, the spring serving to hold the ball latch 25 engaged with any one of the seats 5 in the keeper 4. Within the signal casing 6, the support 2 carries an abutment 26. A compression spring 27 surrounds the support 2, within the signal, and is engaged at one end with the abutment 26, the other end of the spring 27 being engaged with the end plate 11. 100 The spring 27 serves to maintain the polygonal projection 20 on the end plate 11 engaged with the recess 21 in the pulley 19, and, thus, the pulley and the signal casing are connected for rotation. Further, the spring 27 serves to press the pulley 19 against the 105

keeper 4 and to prevent rattling, when the device is in operation, it being practically impossible for the pulley 19 to be spaced far enough from the keeper 4 so that the ball latch 25 may drop out of place.

Flexible elements 28 are wound in opposite directions about the pulley 19 and are connected thereto. The flexible elements 28 extend through a tubular guide 29, supported at 30 in any suitable way, on the body of the vehicle. At their forward extremities, the flexible elements 28 are connected to a cross head 31 mounted on a shaft 32 journaled in bearings 33 carried by the steering column of the vehicle, there being a handle 35 at the upper end of the shaft 32 as shown in Figure 1, the handle being located closely adjacent to the steering wheel of the vehicle. Any suitable means, however, may be employed for imparting rotation to the signal casing 6.

The various surfaces of the body 12 of the signal casing may be lettered or marked as desired. Thus, if preferred, one surface 25 may carry the word "Stop" as shown at 36, another surface carrying the word "Go" as shown at 37, the remaining surfaces of the body 12 of the signal being marked with oppositely pointing arrows 38 and 39 or their equivalents.

In practical operation, when rotation is imparted to the shaft 32 through the instrumentality of the handle 35, the cross head 31 on the shaft will actuate the flexible elements 28, the flexible elements rotating the pulley 19, and with it the signal casing 6. The operator, at will, may expose any of the various surfaces of the signal body 12, the markings shown in Figure 8 thus being visible, one at a time. The spring 24 permits the ball latch 25 to yield, and to pass from one of the seats 5 in the keeper 4 to another of the said seats, the seats 5 being so located that when the ball latch 25 is in one of them, one of the surfaces of the signal and its corresponding legend or mark, will be disposed rearwardly for observation by those approaching the vehicle from behind. After nightfall the electric lamp 3 50 will illuminate the various surfaces of the body 12 of the signal and the rays of the lamp, proceeding through the transparent

pane 9, will serve to illuminate the license tags (not shown) on the vehicle.

What is claimed is:

1. In a device of the class described, a shaft, a signal journaled on the shaft, a keeper on the shaft and external to the signal, a latch carried by the signal and cooperating with the keeper, means for rotating the signal, an abutment carried by the shaft and located within the signal, and a compression spring within the signal and interposed between one end of the signal and the abutment and serving to thrust the signal longitudinally of the shaft and toward the keeper.

2. In a device of the class described, a shaft, a signal journaled on the shaft, a keeper on the shaft and external to the signal, an operating member interposed between one end of the signal and the keeper, interengaging elements on the signal and on the operating member, coacting to hold the operating member and the signal together detachably for rotation, an abutment carried by the shaft and located within the signal, a compression spring located within the signal and engaging the abutment and the one end of signal and serving to maintain said interengaging elements in co-operating relation and to press the operating member against the keeper, and latch mechanism carried by the signal and by the operating member and cooperating with the keeper.

3. In a device of the class described, a support, a keeper on the support, a signal journaled on the support, an operating member interposed between the signal and the keeper, detachably interengaged mechanism for connecting the operating member with the signal, spring means for thrusting the signal toward the keeper to render said mechanism operative and latch mechanism carried by the signal and the operating member and cooperating with the keeper.

In testimony that I claim the foregoing as my own, I have hereto affixed my signature in the presence of two witnesses.

JOHN L. NUTE.
